UNITED STATES PATENT OFFICE.

HARRY L. WILLIS, OF CHICAGO, ILLINOIS, ASSIGNOR TO UNION SPECIAL MACHINE COMPANY, OF CHICAGO, ILLINOIS, A CORPORATION OF ILLINOIS.

OVERALL-SUSPENDERS AND THE METHOD OF MAKING THE SAME.

1,238,611.

Specification of Letters Patent. Patented Aug. 28, 1917.

Application filed October 9, 1916. Serial No. 124,638.

To all whom it may concern:

Be it known that I, HARRY L. WILLIS, a citizen of the United States, residing at Chicago, in the county of Cook, State of Illinois, have invented certain new and useful Improvements in Overall-Suspenders and the Methods of Making the Same, of which the following is a description, reference being had to the accompanying drawing and to 10 the figures of reference marked thereon.

The invention relates to new and useful improvements in overall suspenders and the method of making the same, and more particularly to an overall suspender having an 15 elastic web intermediate its ends.

An object of the invention is to provide a suspender for overalls wherein the strap is formed by folding the fabric so that the edges meet midway between the side edges 20 of the finished strap and are secured to the body portion of the strap by stitching the same thereto, and wherein the web is inserted within the folded end of the strap and secured therein by a line of stitching passing 25 transversely across the strap.

A further object of the invention is to provide an improved method of making a suspender for overalls which consists in forming the strap by infolding a section 30 of fabric so that the edges thereof meet midway between the side edges of the strap, stitching said edges to the body portion of the strap, removing the side edges from the line of stitching adjacent the end of the strap 35 so as to leave said side edges free, thus forming an open pocket, and subsequently inserting an elastic web within the pocket and securing said free side edges to the web and the body portion.

40 In the drawings, which show by way of illustration one embodiment of the invention:—

Figure 1 is a perspective view of a suspender strap embodying my improvements;

45 Fig. 2 is an enlarged front view of a portion of the suspender;

Fig. 3 is an enlarged rear view of a portion of the suspender;

Fig. 4 is a sectional view on the line $a-a$ 50 of Fig. 3;

Fig. 5 is a sectional view on the line $b-b$ of Fig. 3;

Fig. 6 is a sectional view on the line $c-c$ of Fig. 3;

55 Fig. 7 shows a front view and edge view

of a portion of a fabric blank for forming the strap and the manner of folding the same.

The invention consists both in the overall suspender as an article of manufacture and 60 in the method of making the same. I will first describe the article, and then the method of manufacturing the said article.

My improved suspender for overalls consists of a strap 1, an elastic web 2 and a tab 65 3. The strap may be provided with a fastener 4, while the tab is provided with a button hole 5. Suspenders of this general character are old in the art, and my invention is directed particularly to the manner 70 of folding the fabric to form the strap and the web, and the manner of attaching the web to the strap and tab. The strap and the tab are formed in precisely the same manner, and a description of one will answer for 75 the other.

A fabric blank F has its end to which the web is to be attached turned in, as indicated at 7. The edges are then turned in on the lines 6—6, and then the fabric is folded on 80 the lines 7—7 so as to bring the edges, indicated at 8—8 close together midway between the side edges of the strap, as indicated in Fig. 3. Parallel lines of stitching 9—9 are passed through these edges and through the 85 body portion of the strap. The side edges 8—8 at the point 10 are drawn back so as not to be engaged by these parallel lines of stitching and, therefore, these side edges are free from these points to the ends of the 90 strap, thus forming an open pocket. The web 2 extends within the open pocket of the strap, and a line of stitching 11 is passed through the side edges of the strap, the body portion of the strap and the web securing 95 these parts together. This line of stitching 11, as indicated in Fig. 3, is in the form of a rectangle, as illustrated, although it may be otherwise made. As a matter of fact, in the place of stitching any other securing 100 means may be used, the essential feature being the securing of the web to the strap and the closing of the pocket containing the same.

From the above description, it will be apparent that I have provided a suspender strap wherein the elastic web is secured to the strap and the tab by a very strong and durable connection which is also very neat in appearance. The edges of the fabric 110

forming the strap and tab being turned in, and the folded edges meeting intermediate the side edges of the strap and the tab bring the strengthened portion of the strap formed by these infolded edges and the line of stitching centrally of the suspender. Furthermore, as these lines of stitching pass through the inturned edges of the fabric forming the strap or the tab and the body portion there-
5 of, said strap is prevented from twisting and is held flat.

10 My improved method of making the strap consists in folding the end of the fabric blank, as indicated at *f*, and then passing said fabric blank through the folder of a sewing machine, so that said blank will be folded at its edges and at its sides, as described above, so as to bring the infolded edges centrally of the finished strap. Thus 15 folded, the strap is guided to a stitching mechanism having two needles which pass lines of stitching through the edges of the fabric and through the body portion of the strap, thus joining the infolded edges to the 20 body portion of the strap. At a portion adjacent the end of the strap which may be either the beginning or the ending of the operation of the stitching, these inturned edges are withdrawn from the path of the needles. 25 so that the lines of stitching pass only through the body portion of the strap. This finishes the strap, leaving the edges adjacent the end thereof free from stitching.

30 In the next operation, the elastic web is inserted in the pocket formed by the free end of the strap substantially to the point where the folded edges of the fabric are withdrawn from the lines of stitching, and then the strap and web are stitched together 35 by a line of stitching which extends transversely across the end of the strap and passes through the infolded sides of the strap, the web and the body portion of the strap. This line of stitching may be in the 40 form of a rectangle or otherwise, the essential feature being when stitching is used that the line of stitching extend transversely of the strap. It is obvious that other means 45 may be used in place of stitching, the essential feature being the joining of the web to the strap and the closing of the pocket containing the web.

50 While I have described the method of forming the particular article forming the subject-matter of this application, it will be understood that this method may be used for making shoulder straps for overalls which differ from the specific article herein set forth. The essential feature of the 55 method consists in the stitching of the strap on a sewing machine, completing the strap except that its edges are left free at the end where the web is to be attached, inserting the web, and then sewing (preferably by 60 stitching on another machine) the free ends

65 to the web and the body portion of the strap to the web for securing the same together. In other words, the essential feature is the leaving of the strap open in the first operation to form a pocket, the inserting of the 70 web in the pocket, and then the closing of the pocket and securing the strap to the web, thus making a strong suspender which is also neat in appearance.

75 It is obvious that minor changes in the details of construction and arrangement of parts may be made without departing from the spirit of this invention, as set forth in the appended claims.

Having thus described the invention, what 80 is claimed as new is:—

1. A suspender for overalls comprising a strap having its sides infolded so as to bring the edges thereof adjacent to each other centrally of the rear portion of the strap, parallel lines of stitching passing through said infolded sides adjacent the edges thereof and through the body portion of the strap, said parallel lines of stitching adjacent the 85 ends of the strap passing through the body portion only, a web having one end extending within the strap between the body portion thereof and the infolded sides, and means for securing the infolded sides, the 90 web and the body portion of the strap together. 95

2. A suspender for overalls comprising a strap having its ends turned in, its edges infolded, and its sides infolded, so that the folded edges meet midway between the side edges of the strap in rear thereof, parallel lines of stitching passing through the folded edges and the body portion of the strap, said lines of stitching passing through the body portion of the strap only adjacent the 100 end of the strap so as to leave the infolded sides free, a web having one end extending within said strap between the infolded edges of the strap and the body portion thereof, and a line of stitching extending transversely of the strap and passing through said free infolded sides of the web and the 105 body portion of the strap. 110

3. The method of forming a suspender for overalls consisting in folding a fabric blank so as to bring the infolded sides midway between the side edges of the strap, passing parallel lines of stitching through said infolded edges and the body of the strap, removing said infolded side edges from the 115 path of the stitching mechanism adjacent the end of the strap so that the lines of stitching pass only through the body of the strap, placing the end of an elastic web 120 within the strap between the body portion and the infolded side edges, stitching by a transverse line of stitching the infolded side edges of the web and the body portion together for securing the web to the strap. 125

4. The method of forming a suspender 130

for overalls consisting in longitudinally folding a fabric blank, stitching the side edges to a point adjacent one end to form a strap and leaving the folded side edges of the strap free from stitches at said end to form an open pocket, inserting one end of an elastic web within said open pocket, and securing said strap and web so as to finish

the end of the strap and secure the web thereto.

In testimony whereof, I affix my signature, in the presence of two witnesses.

HARRY L. WILLIS.
